CLAIM

The ornamental design for a weighted training vest, as shown and described.

DESCRIPTION

FIG. 1 is a front elevational view of the weighted training vest embodying my new design;

FIG. 2 is a top plan view thereof;

FIG. 3 is a rear elevational view thereof;

FIG. 4 is a bottom plan view thereof; and,

FIG. 5 is a right side elevational view of the weighted training vest, the left side elevational view being a mirror image thereof.

The broken line showing of the torso in FIG. 1 is for illustrative purposes only and forms no part of the claimed design.
